UNITED STATES PATENT OFFICE.

DALLAS KNOWLTON, OF WASHINGTON, DISTRICT OF COLUMBIA.

JAR-CLOSURE.

967,936.

Specification of Letters Patent. Patented Aug. 23, 1910.

Application filed December 8, 1909. Serial No. 531,998.

To all whom it may concern:

Be it known that I, DALLAS KNOWLTON, a citizen of the United States, residing at the city of Washington, in the District of Columbia, have invented new and useful Improvements in Jar-Closures, of which the following is a specification.

My invention relates to hermetically sealed closures for glass jars, bottles, tumblers and the like, and has especial reference to pressure cap closures, otherwise known as vacuum closures.

An object of my invention is to so construct a closure means, which when the cap is pressed downwardly in the act of sealing the jar it will exert a properly applied lateral pressure or compression upon the gasket or washer employed, in a manner to obtain a perfect seal without a tendency to displacement or distortion of the gasket.

A further object of my invention is to provide a substantially vertical seat for said gasket that is formed integral with the jar by an easily formed annular bead, that is inexpensive to provide.

Another object of my invention is to provide a seal, in which the ordinary normally flat and thin washer now employed in the "Mason" type of jar can be utilized without change to provide a vertically disposed seal.

A further object of my invention is to provide in connection with the pressing cap, a venting means, that will aid in the application of the cap during the exhausting and sealing operation, as well as assisting in the operation of the release and removal of the cap, after a vacuum has been obtained.

In the hermetical sealing of jars by means of a gasket and compression cap, a common type of closure has been that in which the sealing pressure has been applied to the gasket at an angle with the direction in which the cap moves, while effecting the seal, thereby involving a wedging action or closure.

In carrying out such wedging action or closure plan it has been found that the more nearly the pressing surfaces approach a parallel relation to the direction of movement of the cap, the greater the difficulty of maintaining the cap in a level position upon the gasket not only during the sealing operation but in the subsequent handling or transportation of the sealed jar. Furthermore, the nearer the pressing sur-

faces approach a parallel relation to the movement of the cap, the more the frictional contact between the cap and the washer tends to cause the displacement of the latter in the direction of movement of the cap.

It is therefore a purpose of this invention to provide a construction and arrangement of closure elements that will admit the bringing of the pressing surfaces into substantially parallel relation to the direction of movement of the cap, with a properly applied pressure on the sealing member, *i. e.*, whereby the washer is compressed by a biting contact with its seat to provide a seal of reduced contact through which air cannot pass in a manner to positively hold the sealing member from displacement while maintaining the cap in a level position. This is accomplished without the employment of the special construction of reinforcing shoulders recesses and the like, that have hitherto been proposed.

To this end my invention consists generally of a means for supporting and retaining the working face of a sealing gasket or washer in a plane substantially coincident with the direction of movement of the cap, while allowing of its compression at substantially right-angles to the movement of the cap. Said means involves the employment of an annular guide and seating ring or bead extending laterally from the jar together with the utilization of the pressure of elasticity of the slightly stretched gasket for retaining itself in position on the laterally extending reduced contact portion of said bead, against the resistance of which hugging action the frictional contact of the pressing cap has a non-effect in its tendency to displacement while the increasing effect of lateral pressure of said cap at right angles to its line of movement, produces a properly applied pressure in the compression of the seal to secure a closure.

That my invention may be better understood I have illustrated in the accompanying drawings one form of embodiment thereof, without intending, however, to limit my invention in its usefulness to the exact embodiment which I have shown.

Referring to the accompanying drawings, Figure 1, represents a vertical sectional view of the upper portion of the jar constructed in accordance with my invention, showing

cap and sealing gasket in separation. Fig. 2, shows a like view of the jar with the washer shown applied in normal position and the cap removed. Fig. 3, shows a similar view with the cap and washer shown in closure position and relationship. Fig. 4, shows a side elevation of the jar with cap applied and after the vacuum has been established.

- 10 Like numerals indicate like parts in the several figures.
 Referring to the drawings by numeral 5, designates the upper body portion of the jar, which is made preferably of glass 15 pressed into shape, and which is shown as having formed exteriorly on its neck 6, a short distance below its top or mouth 7, a circumferential or annular rib or bead 8, that is preferably V-shaped or cone-shaped 20 in cross-section, and which serves as a means for supporting, retaining and seating the sealing gasket in the required vertical plane. The bead thus shaped is so positioned that its point 9, projects substantially at right- 25 angles from the neck of the jar. In connection with the jar thus constructed I employ the gasket or washer 10, which comprises the ordinary normally flat thin elastic ring, and which constitutes the sealing 30 member of this closure device.

In the normal application of the gasket or washer to the neck of the jar, it is seated as shown in Fig. 2, so as to be stretched over and about the reduced contact portion 35 or point 9 of the bead 8, while the overlapping extensions of said gasket project above and below said point. It will be observed that the gasket is disposed not only to provide a substantially vertical working face 40 of reduced circular contact but said washer hugs its laterally extending seat in a manner to give it stability of position.

11, designates a cup-shaped cover or pressure-cap, that is made or struck up from thin metal, to provide a top portion 12, and an integral depending resilient flange or rim 13, that is flared slightly at its free circumferential edge 14, and which provides that the inner diameter of same will be 50 sufficient to allow the cap to be brought in such relationship and adjustment with the washer as to gently press down the lower overlapping extension of the latter into a substantially vertical plane without permitting the lower edge of the cap to catch or bite into the washer, while the inner diameter of the cap above the flared portion thereof is of less diameter than the combined diameter of the gasket and supporting 55 and seating member, whereby the inner wall of the flange is brought into lateral pressure contact with said washer at a point opposite the abutting projection 9, of the bead 8, to provide a circle of contact with 60 increasing pressure as the cap is pressed

downwardly. In the hermetical sealing of a jar by such a means it will be found that when the jar is filled with a liquid, and the sealing pressure is applied, that a pocket of air will collect between the surface of the liquid and the top of the cap, that will act to cushion in opposition to the proper seating of the compression cap. Therefore, to assist in exhausting the air from the space between the surface of the liquid and the top of the cap, I provide oppositely disposed vent holes 15, that are so located that the air pocketed can escape therethrough during the initial downward movement of the cap in the closing operation but which 75 vent holes on account of their location near the lowermost or flared portion of the flange, will be carried to a point just below the bead where they will be effectively closed by the outer face of the washer, when the 80 cap is pushed to the limit of its downward movement. These vent holes, likewise will serve to aid in the release and removal of the cap after a vacuum or partial vacuum has been obtained, in that the slightest movement of the cap upward again brings the 85 holes above the bead 8, and in open relation with the interior of the jar, to thereby cause the destruction of the vacuum and allow of the ready release of the cap. 90

The operation of applying the cap is apparent from the foregoing description, while it will be observed that upon pressing the cap down after it has been brought in the adjustment shown in Fig. 2, the washer is 100 bent downwardly over the projection 9, of the bead, in such a manner that the point not only forms a supporting seat in the proper plane that is hugged by the elastic washer but which presents a form of abutment that bites into the contacting portion of the washer thereby providing by its embodiment an added retaining effect on the washer to resist the thrust and frictional contact of the downpressing flange of the cap, which in turn produces a compression effect on the washer at substantially right angles to its line of travel, with a corresponding increase in the lateral strain upon the walls of the flange of the cap as it is 110 pressed to its downward limit of adjustment in the closing operation. Thus it will be observed that the washer is positively held from downward displacement or distortion during the operation of cap closure or compression, while there is provided a reliable and perfect seal. 115

Having described my invention, what I desire to claim as new and useful is:

In combination, a jar having an annular 125 vertical neck, an external bead triangular shaped in cross-section to form a sharp outer edge, a free, flat rubber gasket resting on the sharp outer edge of the bead, a cup-shaped cap, flaring at its lower edge, having 130

perforations just above the flared edge for the escape of air when the cap is being seated, the cap adapted to cause a biting engagement of the gasket with the sharp edge of the shoulder and the perforations being below the bead when the cap is in sealing position on the jar, for the purpose set forth.

In testimony whereof I have hereunto set my hand in presence of two subscribing witnesses.

DALLAS KNOWLTON.
